UNITED STATES PATENT OFFICE.

WILLIAM RICHARD WHITE, OF BLOOMINGTON, ILLINOIS.

DESIGN FOR A HINGE-STAPLE.

SPECIFICATION forming part of Design No. 31,281, dated July 25, 1899.

Application filed June 24, 1899. Serial No. 721,784. Term of patent 14 years.

To all whom it may concern:

Be it known that I, WILLIAM RICHARD WHITE, a citizen of the United States, residing at Bloomington, in the county of McLean 5 and State of Illinois, have invented and produced a new and original Design for Hinge-Staples, of which the following is a specification, reference being had to the accompanying drawings, forming part thereof.

Figure 1 is a side view of a hinge-staple, showing my new design; and Fig. 2 is a sectional view taken on the line $x-x$ of Fig. 1.

The leading feature of my design consists of a body member and two legs at one side 15 thereof at right angles thereto and connecting portions between the ends of the body member and the legs, the connecting portions being at obtuse angles to the body member.

Thus, referring more particularly to the

drawings, A indicates the body member, B B 20 the legs at right angles thereto and having threaded portions $b-b$ at their outer ends, and C C are the connecting portions between the ends of the body member and the inner ends of the legs and arranged at obtuse angles to 25 the body member.

Having described my invention, what I claim as new, and desire to secure by Letters Patent, is—

The design for a hinge-staple substantially 30 as herein shown and described.

In testimony whereof I have signed my name to this specification in the presence of two subscribing witnesses.

WILLIAM RICHARD WHITE.
Witnesses:

WILLIAM ECKERT,
WALTER E. MAYNARD.
